(57) **CLAIM**

The ornamental design for a tunneling tool for an implantable monitoring device, as shown and described.

DESCRIPTION

FIG. 1 is a top, front, distal side (i.e. perspective) view of the tunneling tool for an implantable monitoring device with a distal end on the left side and a proximal end on the right side;

FIG. 2 is a front side view of the tunneling tool for an implantable monitoring device with a distal end on the left side and a proximal end on the right side;

FIG. 3 is a rear side view of the tunneling tool for an implantable monitoring device with a distal end on the right side and a proximal end on the left side;

FIG. 4 is a distal front view of the tunneling tool for an implantable monitoring device;

FIG. 5 is a proximal rear view of the tunneling tool for an implantable monitoring device;

FIG. 6 is a top view of the tunneling tool for an implantable monitoring device; and,

FIG. 7 is a bottom view of the tunneling tool for an implantable monitoring device.

The broken lines in the drawing depict environmental subject matter only and form no part of the claimed design.
